United States Patent

Des. 240,436
Patented July 6, 1976

240,436

AQUARIUM STAND

Samuel Rosenberg, Brooklyn, N.Y., assignor to
Excelsior Pet Products, Inc., Brooklyn, N.Y.

Filed Mar. 10, 1975, Ser. No. 556,627

Term of patent 14 years

Int. Cl. D6—06

U.S. Cl. D30—12

FIG. 1

FIG. 2

FIG. 3

FIG. 4

FIG. 1 is a perspective view of an aquarium stand embodying my new design;

FIG. 2 is a front elevational view;

FIG. 3 is a right end elevational view; and

FIG. 4 is a bottom plan view of the aquarium stand. I claim:

The ornamental design for an aquarium stand, as shown and described.
